CLAIM

The ornamental design for a ball, as shown and described.

DESCRIPTION

FIG. 1 is a front view of a ball showing my design;

FIG. 2 left front perspective view thereof;

FIG. 3 is a left side view thereof;

FIG. 4 right top perspective view thereof;

FIG. 5 is a rear top perspective view thereof;

FIG. 6 is a top front perspective view thereof; and,

FIG. 7 is a bottom plan view thereof.

The even-length broken lines show the remainder of the article, are directed to environment, represent unclaimed subject matter, and form no part of the claimed design. The long-and-short broken lines form an unclaimed boundary around the claimed subject matter and form no part of the claim.
